CLAIM

The ornamental design for a figurine, as shown and described.

DESCRIPTION

FIG. 1 is a top front isometric perspective view of a figurine showing the new design;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top plan view thereof; and,

FIG. 7 is a bottom plan view thereof.

The evenly spaced broken lines and unshaded areas form no part of the claimed design. The long and short broken lines define bounds of the claimed design and form no part thereof. The various directional adjectives used in this specification, such as "front," "rear," "side," "top," and "bottom," refer to the figurine as illustrated.
